DESIGN FOR A REFRIGERATOR CABINET OR SIMILAR ARTICLE

John R. Morgan, Oak Park, Ill., assignor to Sunbeam Electric Manufacturing Co., Evansville, Ind., a corporation of Indiana

Application July 8, 1939, Serial No. 85,923

Term of patent 3½ years

To all whom it may concern:

Be it known that I, John R. Morgan, a citizen of the Republic of Guatemala, residing at Oak Park, in the county of Cook and State of Illinois, have invented a new, original, and ornamental Design for a Refrigerator Cabinet or Similar Article, of which the following is a specification, reference being had to the accompanying drawing, forming a part thereof.

Fig. 1 is a perspective view of a refrigerator cabinet or similar article showing my design.

Fig. 2 is a side elevational view taken as indicated by the line 2—2 in Fig. 1.

Fig. 3 is a top plan view of the same.

I claim:

The ornamental design for a refrigerator cabinet or similar article, substantially as shown.

JOHN R. MORGAN.
